UNITED STATES PATENT OFFICE

2,466,283

RAILROAD TIE

Milroy G. Stackhouse, Birmingham, Ala.

Application April 16, 1946, Serial No. 662,572

1 Claim. (Cl. 238—72)

1
This invention relates to a railroad tie and more particularly to improvements in a metal railroad tie as exemplified in my Patent 2,128,272 of August 30, 1938.

It is an object of my invention to provide an improved metal railroad tie formed of sheet metal and having a composition or wood filler below the rail sections to support the weight of the trains.

Another object of the invention is to provide a railroad tie formed of correlated sheet metal sections which form a box-like structure whereby a filler may be inserted into the ends of the tie to support the rails and to provide an adapter plate to anchor the rail to the tie.

Still another object of this invention is to provide a metal railroad tie and an adapter plate for the tie to adapt all sizes of rails to the tie by using an adapter of the proper size to anchor the particular sized rail section to this one tie.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings,

Figure 1 is a top plan view of the tie and adapter plate,

Figure 2 is a vertical section of the tie and adapter plate with a rail in place,

Figure 3 is a vertical section taken on the line 3—3 of Figure 1,

Figure 4 is an end elevation of the tie and adapter of Figure 1.

Figure 5 is a plan view of a modified form of the tie and adapter plate,

Figure 6 is a side elevation of the rail in Figure 5,

Figure 7 is a section on the line 7—7 of Figure 5,

Figure 8 is a second modified form of adapter,

Figure 9 is a tool for assembly and disassembly of the tie and adapter plates.

Referring to the drawings, the numeral 10 designates generally an improved railroad tie constructed according to an embodiment of my invention. The tie 10 is formed of two flat metal sheets or plate members 11 and 12 of steel, or other suitable material, so formed and secured together to form an elongated hollow box-like structure or tie. The plate members 11 and 12

are secured together by upper and lower correlated longitudinal ribs 13 and 14 which are fixed together by engaging U-shaped clamping members 15 into the apertured section 16 of the adjacent rib. A rectangular opening 17 is provided in the upper surface of the tie 10 at each end thereof so that the filler 18 is exposed to the rail 19 and rail tie adapter 20.

Filler blocks 18 are provided to be inserted into the ends of the ties 10 at each end thereof to provide a substantial base for the rails 19 and adapters 20. The filler blocks 18 may be solid of a suitable wood as kiln dried, creosoted, oak or of a preformed composition of suitable strength 15 which need not be solid but may be formed as a hollow plug as shown in Figure 3. Suitable tongues, as 21 and 22, may be formed on or struck from the sides of the ties to secure the filler 18 from movement from or within the tie 20. The upper surface of the tie 10 and tie plate members 11 and 12 is formed also with portions 23 which overlie the cutout section or opening 17 to form locking members or anchors 23 which are adapted to clamp over the base flange of the 25 adapter 20.

The adapter 20 is formed of a metal base 24 having a pair of upstanding tongues or keepers 25 formed integrally therewith spaced inwardly from the side edges of the base so that the base 30 is also provided with base flanges 26. It is preferred that the adapter or tie plate 20 be cast in one piece and then cut in two so that the plate 20 itself will provide a certain degree of adjustment to fill various sized rails.

In the use and operation of this tie 10 and adapter 20 the plug 18 is first inserted into the hollow metal tie 10 and fixed in place by bending over the tongues 21 and 22. The tie 10 is placed under a rail 19 and raised so that the adapter 20 may be driven between the block 18 and rail 19. Peening down the corners of the overlapping portion of the upper wall of the tie plate over the adapter securely locks all parts of the tie in place.

With this type of adapter 20, it may be more desirable to construct the hollow metal tie without the overlapping flanges by welding the sections together and installing the end blocks 18 at the factory.

A slightly modified form of tie and adapted plate is shown in Figures 5 to 7, wherein the top wall of the tie members 11 and 12 in the portions 23 which overlie the adapter 20 is formed with an apertured tongue 31 struck from the portion 23. The adapter 20 is formed with openings 32 along

the edge of the outer flange which provide keepers for the tongues 31 in the assembled position. The tongues 31 are hammered down into the keepers 32 to securely lock the adapter 30 to the rail. An opening 33 is provided in each of the tongues 31 for the insertion of a tool 40 to pull the tongue 31 out of the opening 32 when it is desired to remove the adapter 30.

On the adapter 30, the keeper 25 is nearer the outer edge of the flange of the adapter to provide a wider opening between keepers 25, for use with a splice bar adapter 34.

In the use of this adapter 30, the adapter 30 is driven between the rail 10 and block 18, and the tongues 31 hammered into the openings or keepers 32 for locking the adapter 30 to the rail 10.

The adapter 35 shown in Figure 8 is of a type to be used with smaller rails where the flange does not extend outwardly far enough to reach the keeper 25 of the adapter 20. The upstanding lug 36 will stabilize the longer flange of this type of rail tie adapter.

For the assembly and disassembly of the rail 10 and adapters 30, I have provided a special tool 40. One end of the tool 40 has a rounded hammer-head 41 on one side for peening the tongues 31 into the apertures 32, and opposite the hammer face is an outwardly extending cleat 42 which is adapted to be inserted through the opening 33 under the outer edge of the tongue 31 so the tongue 31 may be pried out of the keeper 32. The opposite end 44 of the tool 40 is provided with a hook 45 which is adapted to be engaged with the clamping members 15 on the flanges 13 and 14 for disengaging the interlocked flanges when it is desired to remove the rails 10.

The exact configuration illustrated is regarded as the optimum, but some of the desirable results inherent in this disclosure may be obtained by various slight modifications including some departure from the exact configuration shown,

and it is therefore, requested that the scope of the invention should be regarded as limited only by the terms of the claim.

Having thus described my invention, what I claim is:

The combination of a rail tie comprising a hollow tubular member having a top wall, a filler disposed within said tubular member, said top wall being formed with an opening therein, upwardly inclined anchor members integral with said top wall extending along the edges of said opening transverse of said tie, malleable apertured tongues struck from said anchor members, and a rail tie adapter having horizontally disposed base flanges formed with openings along the edges thereof disposed in said first opening and carried by said filler with said flanges underlying said anchor members, said flange openings adapted to receive said tongues whereby said anchor members will resist vertical displacement of said adapter, said tongues will prevent longitudinal movement of said adapter when engaged with said flange openings, and said tongue apertures constitute means for receiving a prying tool for lifting said tongues out of engagement with said flange openings.

MILROY G. STACKHOUSE.
